Primary Examiner — Shawn T Gingrich*Assistant Examiner* — Anton Dennis Murray(74) *Attorney, Agent, or Firm* — Duane Morris LLP(57) **CLAIM**

I claim the ornamental design for a semiconductor module, as shown and described.

DESCRIPTION

FIG. 1 is a front view of a semiconductor module according to the present invention.

FIG. 2 is a top view of the semiconductor module of FIG. 1. FIG. 3 is a left side view of the semiconductor module of FIG. 1.

FIG. 4 is a rear side view of the semiconductor module of FIG. 1.

FIG. 5 is a bottom view of the semiconductor module of FIG. 1.

FIG. 6 is a right side view of the semiconductor module of FIG. 1; and,

FIG. 7 is a front, top and right side perspective view of the semiconductor module of FIG. 1.

1 Claim, 3 Drawing Sheets(56)
